UNITED STATES PATENT OFFICE.

CARL O. ENGSTROM, OF SACRAMENTO, CALIFORNIA.

SAFETY-RAZOR.

1,226,322.

Specification of Letters Patent.

Patented May 15, 1917.

Application filed August 28, 1915. Serial No. 47,779.

To all whom it may concern:

Be it known that I, CARL O. ENGSTROM, a citizen of the United States, residing at Sacramento, in the county of Sacramento and State of California, have invented certain new and useful Improvements in Safety-Razors, of which the following is a specification.

The present invention relates to improvements in razors, and more particularly to that type of razor wherein the cutting edge of the blade is protected by a guard.

The invention has for its principal objects to provide a razor wherein the angle of the blade is capable of being varied to regulate the position of the cutting edge thereof relatively to the blade support, whereby the beard may be cut at various distances from the skin surface; to provide a razor having a pivotal connection between the handle and the blade holder, the fulcrum point of which is approximately on a line parallel with the cutting edge of the blade, thereby enabling the blade cutting edge to follow the contour of the face; to provide a blade guard which is spaced from the cutting edge of the blade, thereby adapting the blade to cut along its entire cutting edge.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Figure 1 is a view in plan of an embodiment of my improved razor.

Fig. 2 is a sectional view taken on line 2—2 of Fig. 1.

Fig. 3 is a plan view of the blade support removed from the handle.

Fig. 4 is an enlarged sectional view in detail, disclosing the blade adjusted at different inclinations in the blade support.

Fig. 5 is an enlarged detail view of one

of the blade holding fingers disclosing the 55 rolling action of the blade thereover.

Referring more particularly to the several views of the drawings, wherein like characters of reference designate corresponding parts throughout the several views, 1 indicates a suitable flat plate bent upwardly at its opposite side edges as at 2. From each end of the front edge 3 of the plate 1 extend the blade holding fingers 4 having upturned points 5 and upwardly projecting rounded 60 shanks 6. The side edges 2 of the plate extend outwardly beyond the front edge 3 of the plate and are connected by a transverse member 7 downwardly from which project the inwardly curved spaced guard fingers 70 or teeth 8 which terminate on a line slightly in advance of the blade holding fingers 4. The cutting edge 9 of a blade 10 is received in the curved portion of the blade holding fingers 4 and the rear edge of the blade is 75 received in the notches 11 of a yieldable retaining arm 12, preferably positioned centrally of the rear portion of the plate 1 and secured thereto.

The adjustment of the rear edge of the 80 blade 9 in the notches 11 of the arm 12 causes the front portion of the blade to roll on the rounded shanks 6, which will cause the cutting edge 9 to be raised or lowered relatively to the front edge 3 of the plate 1. 85 The spacing of the guard in front of the cutting edge enables the blade to perform a cutting action for its full length.

Fulcrumed in the upwardly bent side edges 2 of the plate 1, with their pivotal axis 90 in a plane approximately parallel with the cutting edge 9 of the blade, are the bent ends 13 of the handle members 14, twisted together as at 15 forming a handle to be grasped by the operator.

A spring 16 is carried by one of the side edges 2 and engages one of the handle members 14 and maintains the blade holder in a plane with the handle 15.

After adjusting the blade for the proper 100 cut of beard, the operator grasps the handle 14 and placing the underside of the plate 1 to the flesh draws the razor downwardly, which causes the guard to first pass over the beard followed immediately by the cutting 105 edge of the blade, which, owing to the arrangement of the guard is capable of a cutting action for its full length. By ful-

crumming the blade holder and handle together on a line approximately parallel with the cutting edge of the blade, the overhang or rear portion of the holder forms a guiding or directing surface, which, during the movement over the flesh causes the cutting edge of the blade to follow the contour of the flesh, the spring 16 serving to normally maintain the plate 1 in a plane parallel with the handle.

10 By withdrawing the bent ends 13 of the members 14 from their fulcrum seats, the handle and blade supporting portion are capable of being easily separated.

15 The blade holder is capable of being shaped or folded from a single piece of metal when desired which enables the same to be easily and cheaply manufactured, and the forming of the handle from a single 20 piece of material enables this part to be manufactured at little cost, and it will be apparent that the invention is capable of being manufactured at little cost, contains but few parts and is capable of being quickly 25 taken apart and assembled when desired.

Having thus described my invention what I claim is:—

1. A safety razor comprising a blade holder, a blade for positioning therein, a 30 guard in advance of the cutting edge of the blade and in spaced relation thereto, and a handle pivotally connected to said blade holder and permitting a movement of the holder independently of the handle when 35 the holder is being drawn across the face, the pivotal axis of which is above the cutting edge of the blade and adjacent the front edge of the holder.

2. A safety razor comprising a blade 40 holder, a blade for positioning therein, a guard for the blade, and an operating handle pivotally connected to said blade holder, the fulcrum point of which connection is located above the cutting edge of the blade 45 holder, whereby the blade holder is permitted to have a movement independently of the handle to allow the same to follow the contour of the face.

3. A safety razor comprising a blade 50 holder, a blade for positioning in the holder, a guard for the blade, means for adjusting the rear edge of the blade to vary the angle of the cutting edge thereof, and an operating handle fulcrumed to the blade holder 55 at a point above the cutting edge of the blade and near the forward edge of the holder, permitting the blade holder to have a movement independently of the handle to allow the same to follow the contour of the 60 face.

4. A safety razor comprising a blade holder, a blade for positioning therein, a guard for the blade, an operating handle fulcrumed to the blade holder above the 65 cutting edge of the blade, said holder being

capable of a movement independently of the handle whereby the blade follows the contour of the face, and means for normally maintaining said blade holder in a plane parallel with said handle.

5. A safety razor comprising a blade holder, a blade removably positioned therein, a guard for the blade, an operating handle extending in a plane at substantially right angles to the cutting edge of the blade and fulcrumed to the blade holder above the cutting edge of the blade and near the forward portion of the holder, permitting a movement of the holder independently of the handle to allow the same to follow the contour of the 80 face, and means for normally maintaining said blade holder in a plane parallel with said handle.

6. A safety razor comprising a blade holder, a blade removably positioned therein, a guard for the blade, an operating handle extending in a plane at substantially right angles to the cutting edge of the blade and fulcrumed to the blade holder near its forward end on an axis approximately parallel with the cutting edge of the blade and capable of a movement independently of the handle when the holder is drawn across the face, and a spring coöperating with the blade holder and handle for normally maintaining the same in a parallel plane.

7. A safety razor comprising a blade holder provided on one edge with blade engaging fingers, a blade having a cutting edge for reception in said blade engaging fingers, 100 and means comprising a spring pressed arm extending at an angle to the lower portion of the blade holder and having a plurality of notches therein for adjusting the angle of the blade.

8. A safety razor comprising a horizontally disposed blade holder provided with blade engaging fingers, a blade having a cutting edge and retained in position by said fingers, and a guard extending parallel with the cutting edge of the blade and including a bar carried by the blade holder and provided with fingers which project toward the cutting edge of the blade and terminate a 110 distance therefrom.

9. A safety razor comprising a horizontally disposed blade holder having upwardly bent side walls and formed with blade engaging fingers, a blade having a cutting edge and retained in position by said fingers 120 and side walls, said blade being capable of adjustment to vary the angle thereof relatively to the blade holder, a guard carried by the upwardly bent side walls of the holder extending at right angles to the 125 holder and spaced from the forward edge of the cutting blade, and means carried by the blade holder for retaining the blade in its adjusted position.

10. A safety razor comprising a blade 130

holder formed with blade receiving fingers, said fingers formed with an upwardly bowed shank, a blade for positioning in said fingers and for projecting beyond one edge 5 of said holder and capable of adjustment to various angles in said holder, and means comprising a resilient arm extending upwardly at an angle from the bottom of the holder for retaining the blade at the various 10 adjusted positions.

11. A safety razor comprising a blade holder, a blade provided with a cutting edge and adapted for positioning in said holder at an angle to the face thereof with the cutting edge projecting beyond one edge of the holder, means for limiting the projecting of the said cutting edge over the edge of the holder, means comprising a resilient arm having spaced blade engaging portions 20 therein arranged in rear of the blade limiting means and on which said blade rests for changing the position of the cutting edge of the blade relative to the holder on the variation of the angular adjustment of the blade 25 in the holder, said resilient arm retaining the blade in its adjusted position.

12. A safety razor comprising a blade holder, a blade provided with a cutting edge and adapted for positioning in said holder 30 at an angle to the face thereof with the cutting edge projecting beyond one edge of the holder, means for limiting the projecting of the said cutting edge over the edge of the holder, means in rear of the blade limiting 35 means and on which said blade rests for changing the angular position of the cutting edge of the blade relative to the holder on the variation of the angular adjustment of the blade in the holder, and means for 40 engaging the blade for forcing the same against the limiting means and for retaining the same in its adjusted position.

13. A safety razor comprising a blade holder formed of a substantially flat plate 45 bent upwardly on opposite sides and said upwardly bent portions projecting beyond one edge of the plate and connected by a cross bar, arranged in parallel spaced relation to the edge which said upwardly bent

portions overhang, and guard teeth disposed 50 along the lower portion of the cross bar and extending downwardly from said bar and terminating short of said mentioned edge of the plate.

14. In a safety razor, the combination 55 with a blade holder, of means for positioning a blade therein with its cutting edge in advance of the holder, and a handle pivoted to the side edge portions of the holder and projected forwardly therefrom, permitting 60 a movement of the holder independently of the handle.

15. In a safety razor, the combination with a horizontally disposed blade holder, of means for positioning a blade therein 65 with its cutting edge in advance of the holder, a downwardly disposed guard plate depending at right angles to the horizontally disposed portion of the holder and spaced from the cutting edge of the blade, 70 and a handle pivoted to the side edge portions of the holder and projected forwardly therefrom.

16. In a safety razor, the combination 75 with a blade holder, of means for positioning a blade therein with its cutting edge in advance of the holder, a handle pivoted to the side edge portions of the holder and projected forwardly therefrom, and spring means for holding the handle in normal 80 alinement with the holder on the release of pressure therefrom.

17. A safety razor, the combination with a blade holder, of means for adjustably positioning a blade therein with its cutting edge 85 in advance of the holder, a guard on said holder extended parallel of the cutting edge of the blade and held above the same in spaced relation thereto, and a handle pivotally connected to the said holder and projected forwardly therefrom. 90

In testimony whereof I have signed my name to this specification in the presence of a subscribing witness.

CARL O. ENGSTROM.
